C. E. SUMMERS,
WRENCH,
APPLICATION FILED NOV. 7, 1921.

1,434,635.

Patented Nov. 7, 1922.

UNITED STATES PATENT OFFICE.

CHARLEY E. SUMMERS, OF NOWATA, OKLAHOMA, ASSIGNOR OF ONE-HALF TO
FORREST I. COWDERY, OF NOWATA, OKLAHOMA.

WRENCH.

Application filed November 7, 1921. Serial No. 513,455.

To all whom it may concern:

Be it known that I, CHARLEY E. SUMMERS, a citizen of the United States, residing at Nowata, in the county of Nowata and State 5 of Oklahoma, have invented certain new and useful Improvements in Wrenches; and I do declare the following to be a full, clear, and exact description of the invention, such as will enable others skilled in the art to 10 which it appertains to make and use the same.

This invention relates to an improved wrench which is especially, but not necessarily designed for use on Ford automobiles 15 for removing or placing in position bolts and nuts.

The principal object of the invention is to generally improve upon tools of this class by the provision of one of extreme simplicity 20 and durability which is practical, compact, convenient to handle, and easy to manipulate.

Another and very important object of the invention is to provide a wrench which embodies an angular head having means for 25 engaging a bolt or nut, together with a handle on which said means is rotatable on an axis parallel thereto to permit it to be inverted or turned throughout an approxi- 30 mate half-circle so that it can be disposed and positively locked in different positions with respect to the handle to enable the tool to be used in limited spaces wherein the bolts or nuts are not easily accessible with 35 the types of wrenches now patented and marketed. Speaking specifically, it may be stated that this improved wrench is primarily designed to enable effective use there- 40 of in removing and replacing the two head- bolts which are disposed under the coil box and the fourth connecting rod bolts. Ordinarily, much time and patience is required in removing or replacing these bolts. How- 45 ever, by using my improved wrench, the task is made comparatively easy.

Another object of the invention is to pro- 50 vide a novel wrench wherein one end of the handle is bent at right angles and then in parallelism to the body portion to offset this portion and to assist in enabling the desired results to be easily accomplished, this handle being detachably and rotatably con-

nected with the rotary work-engaging means to enable these parts to be positioned to obtain the aforesaid results or to permit these 55 parts to be separated and conveniently carried in a tool box on the machine without requiring much space.

Other objects and advantages of the in- 60 vention will be apparent during the course of the following description.

In the accompanying drawing forming a 65 part of this specification and in which like numerals are employed to designate like parts throughout the same:

Figure 1 is an elevational view of the im- 70 proved wrench showing the handle and work-engaging means in the position taken when removing or replacing the aforesaid connecting rod bolts.

Figure 2 is a view like Fig. 1 showing the 75 work-engaging device inverted to enable convenient use of the tool in removing the head-bolts located beneath the coil box.

Fig. 3 is a top plan view of Fig. 1 show- 75 ing the formation of the hand-grip.

Figure 4 is an enlarged detail sectional 80 view taken through the work-engaging means and portion of the handle showing the construction and arrangement of parts more clearly.

Broadly speaking, it will be recalled, as hereinbefore briefly indicated, that the im- 85 proved wrench comprises a work-engaging device including a detachable and rotatable socket member, means for permitting said member to be rotated in one direction or the other or held against rotation, together with a novel handle on which said work-engaging means is turnable on an axis parallel 90 thereto to permit said means to assume either of the positions indicated in Figs. 1 or 2 to permit convenient use of the tool in the places specified.

Referring to the drawing in detail, it will 95 be seen that the above named work-engaging means is generally indicated by the numeral 1 and the handle is designated by the numeral 1^a. The bolt or nut engaging device 1 could be constructed in any suitable way, 100 but, by preference, it comprises a substan- tially L-shaped body 2 at the outer end of which is located a removable combined socket and ratchet member 3. This member 3 is

disposed at right angles to the major portion of the body 2 and is detachably connected therewith by means of a screw 4 which serves the additional function of a 5 journal to permit free rotation of the member 3 with respect to the body. It may be stated here that this socket member is preferably removable because different bolts on 10 automobiles of the aforesaid type are of different sizes and requires different sized sockets for engaging them. The inner enclosed end of the member 3 is formed with teeth 5 and either one or the other of the dogs 6 are designed to alternately engage 15 the teeth for rotating the member in one direction or the other. A coiled spring 7 is connected with the dogs and serves to hold them in engagement with the ratchet teeth. A locking ring 8 surrounds a part of the 20 body 2 adjacent one end thereof and the widened part 9 of this ring is adapted to alternately engage one or the other of the dogs for rendering them effective or ineffective as the case may be.

25 The parts of the wrench so far specifically described are practically the same in construction as conventional ratchet wrenches now commonly used and no claim is made to these details. As before set forth, 30 the novelty of the invention resides in the employment of a different kind of handle and in the idea of mounting the work-engaging means on this handle in such a way as to permit it to be inverted for accomplishing the ends pointed out. Although 35 the connection between the handle and device 1 may be of some other construction, I simply provide the bore of the body 2 with internal screw-threads 10 and the outer end 40 of the handle is externally screw-threaded as indicated at 11 and these threads are engaged with one another to detachably connect the handle and body together and permit the latter to be rotated on the former 45 for changing the relative positions. By carefully examining the sectional view shown in Fig. 4, it will be seen that the screw-threaded end of the handle is equipped with substantially diametrically 50 opposite depressions 12 and that a set-screw 13 passes transversely through the body is adapted to have its inner end projected into one or the other of these depressions for holding the body in either of the positions 55 disclosed in Figs. 1 and 2.

As before suggested and in order to enable a more effective use of the tool in limited spaces, the handle is bent laterally as indicated at 14 and the end 15 is again bent to 60 extend in parallelism with the body portion of the handle. In this way, one end of the handle is offset and experience has taught that by so shaping the handle, the tool can be much more conveniently used for removing the aforementioned connecting rod or

head-bolts. Although it is not absolutely necessary, the handle is formed from a cylindrical rod and this rod is bent upon itself as indicated at 16 and the end thereof brought to bear against the body portion as 70 indicated at 17 and a novel and desirable hand-grip is provided.

When it is desired to remove the connecting rod bolts adjacent the rear end crank shaft bearing, the bolt-engaging device 1 is 75 arranged in the position shown in Fig. 1. Of course, to permit this the set-screw 13 must be first loosened and the entire device 1 turned as a unit around the handle for approximately a half-turn and the set-screw 80 again turned in the opposite direction to position its inner end in the depression 12 which is then brought opposite it. When it is desired to use the tool for removing the cylinder head-bolts which are located beneath the coil box and are ordinarily very difficult to remove and replace, the bolt-engaging device 1 is again rotated on the handle to position it as shown in Fig. 2. The manner of manipulating the locking ring 85 and dogs for rotating the socket member in one direction or the other is, of course, understood and need not be explained here.

By carefully considering the description in connection with the drawings, persons familiar with devices of this class will doubtless be able to obtain a clear understanding of the invention. Therefore, a more lengthy and detailed description is deemed unnecessary.

Since probably the best results may be obtained with the construction and arrangement herein shown and described, this is taken as the preferred embodiment of the invention. However, I wish it to be understood that minor changes coming within the scope of the invention as claimed may be resorted to if desired.

I claim:

1. A wrench comprising a bolt-engaging 110 device including a body having an internally screw-threaded bore, a set-screw passing transversely through said body and having its inner end extending into said bore, a handle having a screw-threaded portion 115 extending into said bore and having its threads engaged with the first named threads, the portion of said handle extending into said bore being formed with approximately diametrically opposite depressions into which the inner end of said set-screw is designed to extend.

2. A wrench comprising a handle formed from a rod bent at right angles intermediate its ends and then bent laterally with respect 125 to the right angularly bent portion to dispose the laterally bent portion in parallelism with respect to the body portion to offset one end of the handle to permit the tool to be conveniently used in places which are 130

not easily accessible, and an angular head on an axis parallel thereto, and coacting on the laterally bent free end of the rod, means between the head and end of rod to positively hold the head in either of its adjusted positions.

5 end and said means and head being rotatable throughout an approximate half-circle around said laterally bent end of the rod

In testimony whereof, I have hereunto set my hand.

CHARLEY E. SUMMERS.
